UNITED STATES PATENT OFFICE.

JOHN FIELDING, OF PROVIDENCE, RHODE ISLAND, ASSIGNOR OF ONE-HALF TO
JOSEPH P. WHITAKER, OF APPONAUGH, RHODE ISLAND.

SAFETY-CATCH.

1,373,124.

Specification of Letters Patent. Patented Mar. 29, 1921.

Application filed April 20, 1920. Serial No. 375,361.

To all whom it may concern:

Be it known that I, JOHN FIELDING, a citizen of the United States, and resident of the city of Providence, in the county of Providence and State of Rhode Island, have invented certain new and useful Improvements in Safety-Catches, of which the following is a specification.

This invention relates to safety catch members for pins, and has for its object to provide an improved construction of keeper which comprises a pair of spaced-apart side ears having marginal, pin-receiving slots, one of said ears being provided with a hollow-center trunnion bridging the space between the ears. On this trunnion is rotatably mounted a guard member which is adapted to co-act with the slots in the ears to admit a pin tongue and lock the same in the keeper.

A further object of the invention is the provision of means for locking the guard member in closed position.

The nature and advantages of the invention will be better understood when the following detail description is taken in connection with the accompanying drawings, the invention residing in the combination and arrangement of parts as claimed.

In the drawings forming part of this specification, like numerals of reference indicate similar parts in the several views and wherein:

Figure 1 is a side elevation of my improved safety catch retaining the point of an ordinary pin-stem.

Fig. 2 shows the keeper as struck from sheet stock before being bent up into operative position.

Fig. 3 is a sectional edge view showing the ears of the keeper as slightly spread apart and the guard member as mounted upon the trunnion which is formed integral with the keeper.

Fig. 4 is a central sectional edge view showing the guard member as mounted upon the central trunnion which bridges the space between the side ears of the keeper.

Fig. 5 is a section on line 5—5 of Fig. 7, showing the two laterally-extending, guard-supporting cross-bars.

Fig. 6 is a perspective view of the guard member.

Fig. 7 is a central sectional side elevation on line 7—7 of Fig. 5, showing the guard

member mounted on the trunnion and closing the marginal slot in the keeper.

Fig. 8 shows the guard member as swung into position to have its marginal slot register with those of the keeper.

Fig. 9 is a modification showing the marginal slots in the keeper as being at the outer edge thereof opposite the base portion and the corresponding slot in the guard as being in position to close the keeper slots when moved to locked position.

With reference to the drawings, 10 designates the usual pin-stem as being mounted in a joint member 11 attached to the body portion 12 of a pin. My improved safety catch member 13 may be connected to the opposite end of the pin body in any suitable way, to receive the pointed end of the pin-stem.

This catch member comprises a keeper member which is preferably blanked out of sheet stock into the shape best illustrated in Fig. 2, having a pair of side ears 14 and 15 connected together by a base portion 16. Each of these ears is provided with a marginal slot 17 which extends inwardly from the edge to the center portion thereof and the ear 14 is shown as being provided with a trunnion 18 which extends laterally from the inner face thereof. The inner surface 85 of the opposite ear 15 is provided with a counter-bore or recess 19 into which the end of the trunnion 18 sets.

After having been struck into the shape illustrated in Fig. 2 the ears 14 and 15 are 90 bent up into the shape illustrated in Fig. 3 providing a base portion 16 between them.

In order to close the marginal slots 17 in these ears so as to securely lock the pointed end of the pin-stem therein, I have provided 95 a guard member 20 which, as best illustrated in Fig. 6, is also provided with a marginal slot 21 which may be caused to register with the slots 17 in the keeper, as illustrated in Fig. 8, for the purpose of admitting the 100 point of the pin-stem therein. The center portion 29 of this guard member is punched out in circular form and is mounted upon the trunnion 18.

After having been positioned on the trunnion, as illustrated in Fig. 3, the side ears are then closed into the position illustrated in Fig. 4, with the guard member between them.

An operating handle 22 is formed on this 110

guard member, which may be engaged by the thumb and finger of the user, to rotate this guard upon its trunnion, and in order to provide a detent or locking means for retaining this guard when its slot has been moved to close those in the keeper, I have provided a cross-bar 23 which is preferably formed integral with the margin of the ear 14 and is bent into position to bridge the space between the two ears, and this operating handle 22 is preferably formed in somewhat of a hook shape having a recess 24 with a slight protuberance 25 near its end adapted to snap over the arm 23 when the guard is moved to closed position.

Another cross-bar 26 also formed on the ear 14 is bent to bridge the space between the ears at the back side of the guard member, which bar serves as a stop to limit the movement of the guard in the opposite direction and cause its slot to register with those in the ears. A slight protuberance 30 is also formed on the edge of the guard to ride under this bar 26 and so serve as a detent to hold the guard in open position.

These arms in addition to the functions described also serve to support the guard member against spreading or opening up when the pin tongue while held therein, is subjected to heavy opening strains.

In some cases instead of forming the marginal slots on the under edge of the keeper ears, I may form them on the upper edge or opposite the base of these ears as indicated at 27 in Fig. 9, in which case the slot 28 in the guard member will be in position to close the ears 27 when moved to locked position.

An essential advantage in forming the trunnion integral with one of the side ears and having its free end engaged by a socket in the opposite ear is that by this construction the spreading tendency of these arms is prevented.

The foregoing description is directed solely toward the construction illustrated, but I desire it to be understood that I reserve the privilege of resorting to all the mechanical changes to which the device is susceptible, the invention being defined and

limited only by the terms of the appended claims.

I claim:

1. A safety catch comprising a keeper having a pair of spaced-apart side ears having their edges connected together at one point to form a base by which they are fixed to a support, one of said ears having fixed to it a hollow center trunnion bridging said space, each ear being provided with a marginal slot leading to said hollow center, and a guard member rotatably mounted on said trunnion having a slot co-operating with said ear slots to open or close them. 55

2. A safety catch comprising a keeper having a pair of spaced-apart side ears having their edges connected together at one point to form a base by which they are fixed to a support, one of said ears having a central recess and the other having an integral hollow center trunnion bridging said space and entering said recess, each ear being provided with a marginal slot communicating with said hollow center and a guard member rotatably mounted on said trunnion and 70 provided with a marginal slot adapted to coact with those in said ears to admit a pin tongue and then lock it therein. 75

3. A safety catch comprising a keeper having a pair of spaced-apart side ears, a trunnion on one of said ears bridging said space, one of said ears having a peripheral bar bridging the space between said ears, each ear being provided with a marginal slot and a hook-shaped operating member in 85 said guard adapted to engage said bar to lock said guard in closed position.

4. A safety catch comprising a keeper having a pair of spaced-apart side ears, one of said ears having a hollow center trunnion 90 bridging said space, each ear being provided with a marginal slot leading to said hollow center, and a guard member rotatably mounted on said trunnion having a slot co-operating with said ear slots to open or 95 close them, and means locking said guard in either open or closed position.

In testimony whereof I affix my signature.

JOHN FIELDING.
